UNITED STATES PATENT OFFICE.

WILLIAM H. PERRY, OF CONCORD, NEW HAMPSHIRE.

DESIGN FOR A MONUMENT.

SPECIFICATION forming part of Design No. 22,372, dated May 2, 1893.

Application filed April 3, 1893. Serial No. 468,942. Term of patent 7 years.

To all whom it may concern:

Be it known that I, WILLIAM H. PERRY, a citizen of the United States, residing at Concord, in the county of Merrimac and State of New Hampshire, have invented and produced a new and original Design for Monuments, of which the following is a specification, reference being had to the accompanying drawing.

My design consists in the configuration of 10 the base, the pedestal, and shaft,—the several forms of ornamentation, and the character of the surface of different parts, all of which will be clearly illustrated in an accompanying drawing forming a part of the following 15 specification and claim.

Referring to the drawing by figures and letters of reference—the base 1 has four vertical sides and terminate at their top in an acute frustum of a pyramid as seen at 2. The 20 pedestal 3, has four vertical sides terminating at their top in an acute frustum 4 of a pyramid, upon one or more sides of which may be formed a raised tablet 5. The shaft 6, has four vertical sides, and is provided with raised tablets 7 and 25 8 on each of its sides; the tablet 7 being at its bottom and of proper dimension to meet the upper lines of the frustum 4, while the tablets 8, are at the top of the shaft 6, and terminate in a four sided pyramid 9, having arched 30 corners 10, gradually diminishing in height from the corners of said tablets 8, to the apex

11, of said pyramid 9. The adjacent edges of each of the tablets 7 and 8, are beveled as at 12, toward the shaft 6. The tablets 7 are grooved as at 13, so as to form the bead 35 14, which is flush (or nearly so) with the vertical sides of said tablets, while the greater portion of the lower edge of the tablets 8, project downward in the form of an inverted arch 15.

The sides of the shaft 6, are ornamented by 40 tablets 16, which are best designated by a surface of a character differing from that of the remaining portions of said shaft, and may be distinguished therefrom by a series of border 45 lines 17, having substantially the configuration shown.

The base, pedestal, and shaft, are further ornamented by surfaces of a different character, for instance,—the surfaces marked by 50 the letter A, are termed rockwork, those lettered B, are hammered work, and those marked C, are polished work.

What I claim is—

The design for a monument substantially 55 as shown and described herein.

In testimony whereof I affix my signature in presence of two witnesses.

W. H. PERRY.
